DESIGN FOR AN OFFICE CHAIR

Kenneth F. Davis and John J. Josephs, Buffalo,
N. Y., assignors to The Sikes Company, Inc.,
Buffalo, N. Y.

Application October 27, 1937, Serial No. 72,471

Term of patent 3½ years

To all whom it may concern:

Be it known that we, Kenneth F. Davis and John J. Josephs, citizens of the United States, residing at Buffalo, in the county of Erie and State of New York, have invented a new, original, and ornamental Design for an Office Chair, of which the following is a specification, reference being had to the accompanying drawing, forming part thereof.

The figure is a perspective view of an office chair showing our new design.

We claim:

The ornamental design for an office chair as shown.

KENNETH F. DAVIS.
JOHN J. JOSEPHS.
